The ornamental design for a valve inhibitor for a bottle jack as shown and described.

DESCRIPTION

FIG. 1 is a perspective front view of a valve inhibitor for a bottle jack showing my new design;

FIG. 2 is another perspective front view thereof;

FIG. 3 is an elevational front view thereof;

FIG. 4 is an elevational rear view thereof;

FIG. 5 is an elevational right side view thereof;

FIG. 6 is an elevational left side view thereof;

FIG. 7 is top plan view thereof; and,

FIG. 8 is a bottom plan view thereof.

The broken lines in the figures are for the purpose of illustrating portions of the valve inhibitor for a bottle jack that form no part of the claimed design. The additional broken lines in FIG. 1 showing a bottle jack show environment and form no part of the claimed design.
